ROTOR FOR HAMMER MILLS

Henry J. Mankoff, Wichita, Kans.

Application September 26, 1933, Serial No. 691,049

3 Claims. (Cl. 83—11)

The device forming the subject matter of this application is a cylinder or rotor for a hammer mill, and one object of the invention is to provide an article of the class described which may be made cheaply, the article possessing great strength, and being capable of being set up and taken down readily. Another object of the invention is to provide novel means for mounting the hammers. A further object of the invention is to provide a cylinder for a hammer mill, which will avoid clogging or choking.

It is within the province of the disclosure to improve generally and to enhance the utility of devices of that type to which the invention applies.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 In the accompanying drawings:

Fig. 1 shows in section, a device constructed in accordance with the invention, parts being in elevation, and parts being broken away;

Fig. 2 is a transverse section of the structure shown in Fig. 1;

Fig. 3 is a transverse section showing a modification;

Fig. 4 is a transverse section showing another modification;

Fig. 5 is a sectional view, parallel to the shaft, and showing a further modification;

Fig. 6 is a transverse section, showing a still further modification;

Fig. 7 is a section of the structure shown in Fig. 6, the cutting plane being parallel to the shaft.

In Figs. 1 and 2, there is shown a hammer mill, comprising a casing 1, including the usual perforated concave screen 2. The casing 1 is supplied with bearings 3.

The rotor or cylinder forming the subject matter of this application embodies a shaft 4, journaled for rotation in the bearings 3. Polygonal plates 5 are provided, as part of the rotor, and may be in the form of like equilateral triangles, as disclosed in Fig. 2. The plates 5 have openings 6, receiving the shaft 4 closely. Adjacent plates 5 are mounted on the shaft 4 with their marginal angles 7 out of registration, the marginal angles of one plate extending outwardly

with respect to the edges of an adjacent plate, to render the rotor or cylinder star-shaped in cross section, and to form circumferentially spaced projections 8 thereon. Connections 9, which may be rods, pass through the projections 8 of the plates 5. These removable rods 9 are held in place, against longitudinal movement, by cotter pins or other securing devices 10, engaging the projections 8 of the outermost plates 5, as shown in Fig. 1. The plates 5 are held tightly together, and are held on the shaft 4, against relative rotation with respect to the shaft, by any suitable means, such as nuts 11, threaded on the shaft, and engaging the outermost plates.

The hammers are marked by the numeral 12, and, as shown in Fig. 2, there is one hammer for each of the plates 5. The inner ends of the hammers 12 are disposed between adjoining plates 5 and are mounted on the connectors 9. The inner extremities of the hammers 12 are received in seats 14, formed in the edges of the plates 5, the seats giving an additional bearing, of increased strength, for the inner ends of the hammers.

In Fig. 3, parts hereinbefore described are designated by numerals previously used, with the suffix "a". In this form of the invention, the seats 14 of Fig. 2 are dispensed with, and the inner extremities of the hammers 12a simply abut, as shown at 15, against one of the marginal edges 25 of the plate 5a.

The structure shown in Figs. 2 and 3 provides for a fixed hammer, but it is within the contemplation of the invention that a swinging hammer may be used. Such a construction is shown in Fig. 4. In Fig. 4, parts hereinbefore described have been designated by numerals previously used, with the suffix "b". In Fig. 4, the inner portions of the hammers 12b are cut away at their ends and at their sides, as shown at 16, so that the hammers swing on the connectors 9b.

Sometimes it is desired to use a thicker or heavier hammer, and in this connection, reference is had to Fig. 5, wherein such a hammer is shown and is marked by the reference character 12c. In Fig. 5, parts hereinbefore described have been designated by numerals previously used, with the suffix "c". In this form of the invention, the plates 5c are arranged in pairs, the members of each pair having their marginal angles 1c alined, instead of out of alinement, as shown in Fig. 3. This arrangement gives a wider space 18, to receive the inner end of the hammer 12c, and also forms a double-thick mounting for the connectors 9c.

In Figs. 6 and 7, parts hereinbefore described have been designated by numerals previously used, with the suffix "d". In this form of the invention, the hammers are fixed, because they are held in place by shear rods 21, passing through the inner portions of the hammers 12d and through the projections 8d of the plates 5d. The shear rods 21 are strong enough to hold the hammers 12d rigidly in place, in the ordinary 10 operation of the machine, but if an obstruction is encountered, which might do damage, the rods 21 will shear off, because they are constructed of a material which will permit this operation to take place. The hammers 12d then can swing over, because their inner ends are rounded, as shown at 20, and because their sides are cut away, as shown at 19.

In case wet and rough material is being operated upon, such material will sometimes pass 20 the hammers, and wrap around the shaft 4, for instance. In the present invention, this cannot take place, because the marginal angles 7 serve as cutting elements, which sever the material. The cylinder or rotor, therefore, is kept clean at 25 all times, and is not encumbered with a mass of wound-up material. The construction shown and described provides for the simple construction of a well balanced rotor, since, as shown in Fig. 2, there are six hammers 12 about the periphery of the rotor. By increasing the size of 30 the plates 5, the cylinder may be made as heavy as is necessary, to give a fly wheel effect. Although the triangular form of the plate 5 is the form that is most acceptable, and most effective, 35 the plates need not be of the triangular form shown in the drawings.

Having thus described the invention, what is claimed is:

1. A rotor for a hammer mill, comprising po-

lygonal plates having aligned openings for the reception of a shaft, connections each passing removably and in a single length through all the plates and binding them together in a solid body, the plates having straight marginal edges forming marginal angles, said marginal angles being in alignment in alternating plates, to form spaces between alternating plates, and being out of alignment in adjoining plates, whereby the marginal angles of each plate will form spaced projections, extending beyond the marginal edges of adjoining plates, and hammers extended into said spaces and abutting at their inner ends against said edges, to hold the hammers rigid, the connections passing through the hammers and holding their inner ends in the aforesaid abutting relation, the thickness of the hammers being equal to the width of said spaces, and the marginal angles of the plates being sufficiently acute so as to form cutters, both of the features last enumerated cooperating to prevent material from being wound about the rotor, between the hammers.

2. The rotor of claim 1, wherein, as a further distinction, the plates are in the form of straight 25 sided triangles, symmetrical with respect to said openings, the acuteness of the cutters being enhanced and the effectiveness of the cutters being increased, due to the specific form of the plates, the angles of two adjoining plates forming 30 a six-pointed star.

3. The rotor of claim 1, wherein, as a further distinction, the straight edges of adjoining plates are aligned, to double the width of said spaces and to provide for the use of hammers of correspondingly increased thickness and to double the 35 length of the cutting edges of the cutters.

HENRY J. MANKOFF.
